UNITED STATES PATENT OFFICE.

EUGENE DAUCHER, OF NEW YORK, N. Y.

AUTOMATIC FIRE-EXTINGUISHER.

1,140,960.

Specification of Letters Patent. Patented May 25, 1915.

Application filed July 20, 1914. Serial No. 851,922.

To all whom it may concern:

Be it known that I, EUGENE DAUCHER, a citizen of the United States, and a resident of the city of New York, Woodside, borough of Queens, in the county of Queens and State of New York, have invented a new and Improved Automatic Fire-Extinguisher, of which the following is a full, clear, and exact description.

10 My invention consists of an automatic fire extinguisher and the object in view is to simplify and improve devices of this character in such a manner as to cheapen their structure, facilitate their operation by 15 causing them to operate without extremely excessive heat and to sprinkle the water for the extinguishing of the fire over a large area.

20 A further object of the invention is comprehended in the provision of an automatic fire extinguisher in which the working parts are mounted upon a supply pipe and which includes a rotatable nozzle normally held closed by a readily combustible element composed of a series of cloth or fibrous strands 25 which can be economically renewed to normally hold the nozzle closed, while spring means are provided for normally tending to move the nozzle to an open position upon it 30 being released by the destruction or burning of the threads or fibrous strands.

25 A still further object of the invention is comprehended in the provision of sprinkling means attachable over the nozzle in such 35 a manner that the form thereof may vary, while the operating parts are inclosed in a complete combustible bag or closure, to which a fuse may be attached for hastening the opening of the nozzle of the extinguisher.

40 With the above and other objects in view, the invention resides in the peculiar combination and arrangement of parts to be hereinafter more fully described, illustrated and claimed, it being also an object to provide a device which is simple in construction, durable and efficient in operation and not likely to get out of working order.

45 Reference is to be had to the accompanying drawings forming a part of this specification, in which similar characters of reference indicate corresponding parts in all the views, and in which—

50 Figure 1 is a side elevation of an automatic fire extinguisher constructed in ac-

cordance with my invention, one type of sprinkler being shown and the bag or enclosure being omitted; Fig. 2 is a longitudinal sectional view taken on the line 2—2 of Fig. 1; Fig. 3 is a cross sectional view taken on the line 3—3 of Fig. 1; Fig. 4 is a cross sectional view taken on the line 4—4 of Fig. 1; Fig. 5 is a side elevation of the complete automatic fire extinguisher; and Fig. 6 is a sectional view illustrating the application of another form of sprinkling device to the improved extinguisher.

As illustrated in the drawings, the numeral 10 designates a supply pipe for water, steam or other extinguishing fluid from the mains or other reservoirs under pressure, to the sprinkler end of which a nozzle is provided consisting of a cap 11 which is threaded to the supply pipe as shown at 12 by interior threads on its flange 13 and exterior threads on a reduced portion of the discharge end of the supply pipe so that the exterior surface of the cap and pipe will lie substantially flush. The cap is provided with a pair of spaced segmental or sector-shaped openings 14 located at diametrically opposite points of its center, and an enlarged perforated sprinkling nozzle proper 15 having a flanged portion 16 engaged on exterior threads of the flange 13 of the cap 17 is mounted over the latter to spread the water throughout a large area. This nozzle proper has an end or intermediate wall 17 which is provided with a pair of spaced segmental or sector-shaped openings 18 so located as to be normally disposed at right angles relative to the openings 14, to close the end of the supply pipe. The nozzle provided with the openings 18 and loosely threaded on the cap may be used with or 20 without the perforated enlargement if desired, the water or extinguishing fluid in either instance passing through the openings after the nozzle is rotated on the cap.

For the latter purpose, the supply pipe 10 is provided with an enlargement or shoulder 19 spaced from its discharge end, and a longitudinally extending arm 20 is fixed to said enlargement so as to remain stationary with the pipe. A ring or sleeve 21 is rotatably mounted on the supply pipe between the enlargement 19 and the ring 21 and at its ends is connected to or engaged with the stationary enlargement and the rotatable ring tending to normally rotate the ring and the 25 30 35 40 45 50 55 60 65 70 75 80 85 90 95 100 105 110

nozzle therewith in such a manner as to dispose the openings 14 and 18 in alinement. In order to hold said openings out of alinement and thus close the end of the supply pipe a depending wing 24 is fixed to the ring 21 and between the wing and the stationary arm 20 a plurality of combustible threads or fibrous strands 25 are passed, the same preferably extending through an eye 26 carried by the arm. The spring tends to normally rotate the ring and nozzle in an anti-clockwise direction, but by reason of the threads connected as specified, pull is exerted on the threads against the stationary arm 20 so as to hold the ring and nozzle against rotation while the openings 14 and 18 are out of alinement and the discharge end of the supply pipe is closed against the outlet of water or extinguishing fluid. In this manner, when the threads are ignited or destroyed by the presence of fire or otherwise, although the same are advantageous by reason of their extreme readiness of combustion, the spring will act to rotate the ring on the threads 16 and the movable part of nozzle therewith and by engagement of the arm 20 with a longitudinally extending stop member 27 also fixed to the shoulder 19 and projecting therefrom diametrically opposite to the arm 20, the sleeve will be permitted to turn 90° before the attaching part 28 of the wing 24 engages the stop member 27, while the openings 14 and 18 will be disposed in alinement so as to permit the escape of water. Normally, the threads or fibrous strands are under tension, as shown in Figs. 1 and 3 of the drawings, when they are disposed to connect the wing at the base of a frame which is of triangular form and the arm fixed to the shoulder, and when in this position the spring is contracted, as shown in Fig. 1, but when the threads are burned 45 the spring expands to rotate the ring and nozzle and the nozzle remains open to cause the water or extinguishing fluid to be sprayed or sprinkled over a large area to extinguish any blaze or obviate further destruction.

In order to further insure destruction of the threads or fibrous strands 25 and the opening of the nozzle to allow the discharge of the extinguishing fluid, the parts enumerated, with the exception of the perforated nozzle proper, are covered with a readily combustible inclosure or bag 29 which fits over the supply pipe and around the same beyond the enlargement 19 and in rear of the perforated nozzle, while a fuse 30 is connected to the apex of the frame together with the bag or inclosure, thus presenting a larger surface to the heat or flame to result in the burning of the threads. In lieu of the perforated nozzle 15 a structure much similar to an ordinary lawn sprinkler is employed. the same comprising an attaching

part 31 having a rotatable part 32 with branch pipes 33 having sprinkling nozzles 34 at their ends, all facing in opposite directions to rotate and spread the water or extinguishing fluid over a larger area and to act in the manner of a lawn sprinkler.

By a device constructed in accordance with this invention it will be unnecessary to use a composition material which requires excessive heat in order to result in the opening of the sprinkling nozzles, as in the present instance the threads or fabric including the inclosure or bag are readily combustible as distinguished from the usual material which simply fuses or melts. It will also be obvious that steam or any fire extinguishing fluid may be used in lieu of water and that the device is especially adapted to be placed on the walls or ceilings of steamers where there is inflammable or combustible material stored or where crossed electric wires are situated, and to be arranged in accordance with the advice of any architect, builder or designer of a steamer or whatever building the devices are applied to, such as theaters, factories, stables or the like. The device is very small and compact and by reason of its simple construction can be economically produced and will occupy a minimum of space when in use.

Having thus described my invention, what I claim as new and desire to secure by Letters Patent is:—

1. An automatic fire extinguisher, comprising a supply pipe for an extinguishing fluid having a discharge end with openings therein, a rotatable sprinkling element having openings adapted to aline with the first mentioned openings, spring means surrounding the supply pipe and acting on the rotatable element to move the same in position to cause alinement of the openings and permit the escape of the fluid and a plurality of combustible threads to hold said spring means under tension with the openings out of alinement but adapted upon being burned to permit rotation of said member under the action of the spring to dispose the openings in alinement as specified.

2. The combination with a supply pipe of the class described and having an end portion with openings at diametrically opposite sides of its center; of a cap movably mounted thereon and having similar openings, means tending to move the cap to cause alinement of the openings, and means connected to the cap and supply pipe normally under tension to hold said openings out of alinement against the action of the spring means and adapted upon being broken to permit movement of said cap to cause the openings to aline and permit the escape of the fluid.

3. An automatic fire extinguisher, comprising the combination with a supply pipe

for water or the like having a removable end portion with openings therethrough; of a sprinkling nozzle rotatably mounted, an arm fixed to the pipe and projecting over the rotatable part, a spring fixed to the pipe and to the rotatable part to hold the latter in position to expose the openings, and combustion means between the arm and the rotatable part to be destroyed in the presence 10 of heat for permitting the spring to act.

4. An automatic fire extinguisher, comprising the combination with a supply pipe for water or the like having a removable end portion with openings therethrough; of a sprinkling nozzle rotatably mounted, an arm fixed to the pipe and projecting over the rotatable part, a spring fixed to the pipe and to the rotatable part to normally hold the latter in position to expose the openings, a plurality of threads connected to the arm and to the rotatable part to release the spring upon being destroyed, a combustible bag inclosing said parts, and a fuse connected to the bag and threads.

25 5. An automatic fire extinguisher, comprising the combination with a supply pipe for water or the like having a removable end portion with openings therethrough; of a sprinkling nozzle rotatably mounted, an arm fixed to the pipe and projecting over the rotatable part, a spring fixed to the pipe and to the rotatable part to normally hold the latter in position to expose the openings, a plurality of threads connected 30 to the arm and to the rotatable part to release the spring upon being destroyed, and means to limit the rotation of said rotatable part with respect to the supply pipe to cause alignment of the openings of the removable end and cap.

40 6. The combination with a supply pipe for water or the like having an enlargement spaced from its discharge end, an end wall threaded to said discharge end and having a pair of openings therethrough diametrically opposite to each other, and a cap threaded on said end wall for free rotation, said cap having a similar pair of openings adapted to aline with the first-mentioned 45 openings; of a ring rotatable on the

pipe and connected to the cap at a spaced distance therefrom, a spring coiled on the pipe and connected to the ring and enlargement tending to rotate the ring and cap in one direction, a wing carried by the ring, 55 an arm carried by the enlargement and projecting longitudinally of the pipe, a plurality of fibrous strands connected to the arm and to the wing in spaced convergent relation to be ignited and broken whereby the spring will rotate the ring and cap, and a stop member against which said arm engages to limit the rotation of said parts when the openings are in alignment.

7. The combination with a supply pipe 65 for water or the like having an enlargement spaced from its discharge end, an end wall threaded to said discharge end and having a pair of openings therethrough diametrically opposite to each other, and a cap 70 threaded on said end wall for free rotation, said cap having a similar pair of openings adapted to aline with the first-mentioned openings; of a ring rotatable on the pipe and connected to the cap at a spaced distance 75 therefrom, a spring coiled on the pipe and connected to the ring and enlargement tending to rotate the ring and cap in one direction, a wing carried by the ring, an arm carried by the enlargement and projecting 80 longitudinally of the pipe, a plurality of fibrous strands connected to the arm and to the wing in spaced convergent relation to be ignited and broken whereby the spring will rotate the ring and cap, a stop member 85 against which said arm engages to limit the rotation of said parts when the openings are in alignment, a combustible inclosure over the pipe beyond the enlargement and in rear of the cap, and a fuse leading to the inclosure and fibrous strands at the point of attachment of the latter to the arm.

In testimony whereof I have signed my name to this specification in the presence of two subscribing witnesses.

EUGENE DAUCHER.
